UMBRELLA RIB TIP

Joseph Levin, Lancaster, Pa.

Application December 4, 1940, Serial No. 368,546

6 Claims. (Cl. 135—36)

This invention relates to an improved tip for an umbrella.

In umbrella constructions at present available and in use, it is the practice to provide a tip having a cylindrical inner portion and a tip socket in the cylindrical portion with a transverse opening in the cylindrical portion outwardly of the socket. The cover of the umbrella is initially secured to the tip by turning the cover inside out and also positioning the tip in a reversed position. After the thread is stitched through the opening and about one-half or the whole of the tip adjacent the hole or opening, the tip is turned with its outer end outwardly. With a construction of this kind, the cover usually tears at the opposite ends of the opening through the tip, due to the fact that the strain of the stretched cover is applied on the thread. It is, therefore, an object of this invention to provide an improved tip which will overcome the disadvantages of the present tip in that the strain of the stretched cover will be borne by an abutment carried by the tip.

Furthermore, in stitching the present type of tip onto an umbrella cover, the stitching is done by a machine which is provided with a tip supporting stud, but the operator of the machine is usually required to rotate the tip on the support until the hole aligns with the needle. This requires a careful positioning of the tip and close visible examination by the operator. Another object of this invention is to provide an improved tip which may be mounted on the stitching machine in the proper position by merely the feel of the tip during the mounting operation.

A further object of this invention is to provide a tip of this kind which will not only speed up the attachment of the tip to the cover but will also eliminate the possibility of breakage of the needle through misalignment of the hole with the needle.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

In the drawing:

Figure 1 is a detail side elevation of an um-

rella tip constructed according to an embodiment of this invention.

Figure 2 is a top plan of the tip.

Figure 3 is an inner end elevation of the tip.

Figure 4 is a top plan of the tip partly broken away and in section showing the holding means for holding the tip during the stitching of the cover thereto.

Figure 5 is a bottom plan of the tip showing a fragmentary portion of the cover and the umbrella rib.

Figure 6 is a fragmentary longitudinal section taken on the line 6—6 of Figure 5.

Figure 7 is a fragmentary sectional view taken on the line 7—7 of Figure 6.

Figure 8 is a fragmentary sectional view similar to Figure 7 but showing another form of stitching for holding the cover to the tip.

Referring to the drawing and first to Figures 1, 2 and 3, the numeral 10 designates generally a tip structure which is constructed according to an embodiment of this invention.

The tip 10 includes an inner rib receiving socket 11, a stem 12 extending outwardly from the socket member 11 and an ornamented head 13 which extends outwardly from the stem 12. The stem 12 adjacent the inner end thereof is provided with a transversely disposed opening 14 through which threads are adapted to be stitched in order to hold the umbrella cover on the tip 10. The tip 10 is provided with a pair of laterally extending abutments 15 and 16 which are disposed substantially between the outer end of the socket 11 and the inner end of the stem 12. The abutments 15 and 16 are provided at their outer ends with shoulders 17 and 18, respectively, which are disposed at substantially right angles to the outer side of the stem 12. The abutments 15 and 16 at their inner portions are tapered at an angle as shown at 19 and 20, respectively.

The socket 11 is provided with a pair of diametrically disposed parallel flat faces 21 and with rounded sides 22 which merge with the opposite edges of the flat faces 21. The stem 12 in transverse section is of substantially rectangular configuration. The inner end hereinbefore described is formed with the opposite flat sides or faces 21 which merge with the adjacent faces of the stem 12 in order that when the tip 10 is initially mounted on a tip retaining or holding pin 23, the opposite flat faces 21 of the tip 10 may be disposed in an upper and lower position so that the hole 14 will be positioned ver-

tically. The holding or retaining pin 23 is mounted in a carrier 24 forming part of an umbrella cover stitching machine and the carrier 24 on its lower side is provided with a flat extension 25 against which one flat face 21 of the tip 10 is adapted to engage.

The carrier 24 is also provided with a resilient tip clamping finger 26, which is secured by fastening devices 27 to the carrier 24 and which engages the uppermost flat face 21 of the tip. At the present time, the conventional tips are round in transverse section and in the positioning of the round tip on the holding pin 23, it is necessary for the operator of the machine to turn the tip until the opening 14 is in a vertical needle aligning position. With a tip as constructed according to the invention which is provided with a pair of opposite parallel flat faces 21, the operator of the machine can determine merely by the physical feel of the tip in which manner the tip should be applied to the carrier 14.

In Figures 4, 5 and 6, the tip 10 is shown in applied position on an umbrella cover C which may be formed of fabric, composition material or the like. The cover C is initially turned with the outer side innermost and the tip 10 is initially disposed with the head 13 extending inwardly of the outer marginal edge of the cover C. In this position, the cover C is disposed inwardly of the shoulders 15 and 16, the inner edge 28 being positioned somewhat in the manner shown in Figure 6. The stitching machine is then operated so that the threads 29 will extend through the opening 14 and then wrapped about a small portion of the cover C inwardly from the marginal edge 28 outwardly from the abutments 15 and 16.

The initial position of the cover C is shown in dotted lines in Figure 6 whereas the full lines show the cover C in its right position with respect to the tip 10 and the ribs R. In the position shown in Figure 6 which is the normal position of the cover C with respect to the tip 10, the body of the cover C overlaps that portion of the marginal edge 28 which overlies the abutment 15 so that strain or pull on the cover C will have a tendency to more firmly press the overlapping marginal portion 28 of the cover on the abutment 15.

The abutment 16 will be a lower abutment and if desired the threads 29 may not only be wrapped about and stitched through the cover C as at 30 but may also be wrapped about the stem 12 of the tip as at 31. This wrapping or looping 31 will be positioned outwardly of the abutment 16 so that if the threads 29, 30 and 31 become somewhat loosened, these threads will press against the right angle faces 17 and 18 of the two abutments.

In Figure 8, there is disclosed a slightly modified form of securing the cover C to the tip 10. In this form the stitching or threads 32 are extended through the hole 14 through the cover 16 and then looped about a portion of the cover C engaging over one side of the stem 12 as at 33. The looped portion 33 will be disposed outwardly of the right angle face or shoulder 17 of the abutment 15, but in the present instance the threads or stitching 32 are not subsequently looped about the opposite side of the stem 12 confronting the shoulder 18 as in Figure 7. In other respects the manner of stitching the cover C in Figure 8 is similar in every detail to the manner of stitching the cover as shown in Figures 5, 6 and 7. By providing an improved tip

as herein disclosed, the operation of attaching the tip to the cover and to the rib is not only speeded up but after the tip has been mounted on the rib and secured to the cover, the strain on the cover C which is caused by opening of the umbrella will not have a tendency to tear the cover at the opposite ends of the opening 14 as is the case with tips at present in use. The tips at present in use and available are provided with a cylindrical socket which merges into an ornamented outer end but the hole through which the stitching engages is disposed in the cylindrical portion and any strain on the cover caused by tightening or stretching of the cover when the umbrella is opened will have a tendency to pull the cover along the straight surface of the inner portion of the tip, and this strain is then applied to the cover where the stitching passes through the cover at the opposite ends of the opening in the tip. However, with a tip as hereinbefore described, the stitching will bind the cover against the stem and the stretching of the cover will bind the overlapping portion 28 of the cover on the shoulder 15 so as to thereby relieve the strain on the cover at the opposite ends of the opening 14.

What I claim is:

1. As a new article of manufacture, a tip for umbrellas, parasols and the like, comprising a socket member, a stem extending axially of said socket member, a head on said stem, and a laterally projecting abutment disposed at substantially the junction of said socket and stem, said stem having a transversely disposed opening therethrough adjacent said abutment and extending transversely of said abutment.

2. As a new article of manufacture, a tip for umbrellas, parasols and the like comprising a socket member, a stem extending axially of said socket member, a head on said stem, and a pair of laterally projecting abutments disposed at substantially the junction of said socket and stem, said stem having a transversely disposed opening therethrough adjacent said abutments and extending transversely of said abutments.

3. As a new article of manufacture, a tip for umbrellas, parasols and the like, comprising a socket member provided with a pair of oppositely disposed parallel flat faces extending lengthwise thereof, a pair of abutments extending laterally of the outer end of said member and in parallel relation to said flat faces, a stem extending axially from said socket member and having an opening therethrough transverse to said abutments, and a head on the outer end of said stem.

4. As a new article of manufacture, a tip for umbrellas, parasols and the like, comprising an elongated member formed with a rib receiving outwardly of its inner end and a transverse opening outwardly of said socket, and an abutment extending laterally of said member at a point inwardly of said opening, said abutment coacting with the cover attaching means passing through said opening in holding the cover against tearing.

5. As an article of manufacture, a detachable rib tip for umbrellas, parasols and the like, comprising an elongated body having a rib receiving socket in one end, a head extension on the other end, and a shoulder forming means intermediate said ends, said body adjacent the said shoulder means and between the latter and said head extension end being provided with an opening for

2,283,074

the reception of stitching whereby to attach the covering of the umbrella, parasol or the like.

6. In an umbrella having ribs and a cover for the ribs having spaced portions of the outer margin thereof reverted; a tip disposed on the outer end of each rib having an abutment inwardly of the outer end thereof and an opening therethrough adjacent to and outwardly of

the abutment, and stitchings, each extending through the opening in and engaging respectively about a portion of a tip and within the fold formed by a reverted cover portion to thereby hold the cover to the tips and the reverted portion on the abutment.

JOSEPH LEVIN.
